UNITED STATES PATENT OFFICE

173,177

PARKA

Laura B. Wright, Fairbanks, Territory of Alaska
Application November 17, 1953, Serial No. 27,641

Term of patent 14 years

(Cl. D3—4)

To all whom it may concern:

Be it known that I, Laura B. Wright, a citizen of the United States, residing at the city of Fairbanks, Territory of Alaska, have invented a new, original, and ornamental Design for a Parka, of which the following is a specification, reference being had to the accompanying drawing, forming a part hereof, and wherein:

Fig. 1 is a front elevational view of a parka, showing my new design;

Fig. 2 is a side view thereof;

Fig. 3 is a back view thereof; and

Fig. 4 is a top plan view of the same.

I claim:

The ornamental design for a parka, as shown.
